CONNECTOR PLUG

Carl H. Judisch and Arthur Howarth, Providence,
R. I., assignors to The Whitney Blake Company,
New Haven, Conn., a corporation of Connecticut

Application February 16, 1938, Serial No. 190,783

6 Claims. (Cl. 173—361)

Our invention relates to improvements in a connector plug assembly comprising a connector plug constructed of rigid or flexible material, a multi-terminal connector cord connected within and a blade for each terminal connected within.

An object of our invention is to provide a connector plug, and connector plug assembly which may be constructed of simple parts and which may be easily assembled by merely forcibly inserting the blades within suitable spaced slits therefor in the plug. For this purpose a portion of the slit is preferably constricted and each blade is provided with means whereby when it is inserted within the relatively constricted portion it will stick.

A further object of our invention is to provide a plug assembly which may be readily assembled on the type of assembly machine shown in our copending application for patent, S. N. 190,456, filed February 14, 1938, for Method of and apparatus for assembling contact blades in connector plugs, in accordance with the method shown therein, by the mere forcible power insertion of the blades within the plug as described in said application.

A further object of our invention is to provide a structure wherein the positive insertion of the blade within the connector plug positively clamps its respective terminal within its plug without the necessity of any other means for securing the terminal to the blade or plug. To provide the relatively constricted portions in the blade slits, we preferably construct the inner ends of the blades with teeth on the outer end walls thereof and with a readily expandable interior construction or provide in said assembly cam wedge means to spread the end walls of the inner portions of said blades into contact with the end walls of the slits to positively cause said teeth to be embedded within the walls of said slit as said blades are inserted within said slits to be permanently retained therein.

A further object of our invention is to provide novel different species of this wedge means whether it be in the blade itself or in the plug.

A further object of our invention is to provide a novel type of plug body which may be readily assembled and withdrawn from the mold.

Further objects of our invention are to provide novel types of blades so constructed that they may be embedded within the plug slits as they are forcibly inserted therein.

These and such other objects of our invention as may hereinafter appear will be best understood

from a description of the accompanying drawings which illustrate various embodiments thereof.

In the drawings,

Fig. 1 is a perspective view of a plug assembly constructed in accordance with our invention.

Fig. 2 is a side elevation thereof.

Fig. 3 is a front elevation thereof.

Figs. 4—9 illustrate one embodiment of our invention, Fig. 4 being a diagrammatic end elevation illustrating our improved plug and blade prior to the forcible insertion of the blade within the plug with the cord previously inserted within the plug, a portion of the plug being shown in transverse section; Fig. 5 being a view of the parts shown in Fig. 4 with the inner end of the blade inserted within the plug slit prior to any cam or spreading action of the type of cam or wedge means shown therein; Fig. 6 being a view similar to Fig. 5 after the cam means has started to function to spread the inner portions of the end walls of the blade to forcibly insert them within the inner portions of the end walls of their respective slit; Fig. 7 being a view similar to Figs. 4, 5 and 6 showing the plug assembly in completely assembled relation with the teeth on the inner portions of the blade end walls embedded within the inner portions of the slit end walls; Fig. 8 being a diagrammatic side elevation illustrating a plurality of blades in alignment prior to their insertion within their respective spaced slits, the cord having been previously inserted within the central aperture of the plug and its terminals each projecting outwardly over its respective slit with the plug being shown in longitudinal section and in general being a side elevation of the parts shown in Fig. 4 in end elevation; and Fig. 9 being a view similar to Fig. 8 after the blades have been assembled within their respective slits to clamp the outer ends of each cord terminal between the outer blade side wall and the adjacent slit wall, being in general a side elevation of the assembled parts shown in Fig. 7.

Figs. 10—15 are views respectively generally similar to Figs. 4—9 of an embodiment of our invention employing a different type of cam wedge means to spread the inner portions of the blade end walls to embed the teeth thereof within the inner portions of their respective slit end walls, said wedge means comprising a frangible portion on the end of the blade which becomes broken during insertion to achieve this result.

Figs. 16—21 are views respectively generally similar to Figs. 4—9 and 10—15 of an embodiment of our invention employing a different type of

cam means to spread the inner portions of the blade end walls to embed the teeth thereof within the inner portions of their respective adjacent slit end walls, said cam means comprising an apertured and slitted enlargeable portion on the end of each blade.

In the drawings, wherein like characters of reference indicate like parts throughout, 10 generally indicates a connector plug assembly constructed in accordance with our invention. Said assembly includes a connector plug body 12, a multi-terminal connector cord 14 having the end thereof contained within a central aperture 16 in said plug and having the terminal wires 18 thereof bared and separated at the inner end thereof and a flat contact blade 20 for each terminal thereof adapted to be rigidly contained when assembled within a respective slit 22 therefor in the connector plug. The one piece body 12 is preferably molded of rigid insulating composition material such as Bakelite, cellulose acetate, hard rubber, etc. but may, if desired be molded of flexible material. Said body is provided with a base 24, in our preferred embodiment having an inset central portion 25, a neck 26 and a central aperture 16 extending from said neck 26 through said body 12 to said inset base portion 25. Said body 12 also has spaced longitudinal slits 22 extending inwardly from the base 24 thereof in our preferred embodiment adjacent the outer end of said inset portion 25, and on opposite sides of and connected to said central aperture 16, in our preferred embodiment, by said inset base portion 25. We also provide flat contact blade members 20, one for each terminal, in our preferred embodiment shown two, one for each terminal, of the double terminal connector cord 14 having the inner ends thereof contained within said slits 22 and having teeth 28 on the inner portions 30 of the end walls thereof adapted when inserted in assembled position within said slits as shown in Fig. 7 to become embedded in the inner portions 32 of the end walls of said slits 22. Each blade 20 is also provided with an aperture 34 in the inner end thereof.

Our invention particularly includes the provision of cam wedge means in said plug assembly to cause said toothed inner portions 30 of the end walls of said blades to become embedded in the end wall portions 32 of said slits as said blades 22 are forcibly inserted within said slits to be permanently retained therein. Inasmuch as each terminal 18 of its double terminal connector cord projects prior to assembly outwardly over its respective slit 22, when assembled it will extend through its respective blade aperture 34 and have the end 36 thereof clamped between each outer blade side wall 38 and adjacent slit side wall 40.

60 It is thus apparent that during assembly the cam wedge means functions to enlarge the enlargeable inner portion 42 of each respective blade as said blade 20 is being assembled in its respective slit 22 to positively embed the teeth 28 thereof in the adjacent portions 32 of the slit wall and to firmly clamp the end 36 of the terminal between the outer surface of its respective blade side wall and slit outer side wall.

70 It is apparent therefore that our improved construction provides an assembly which may be assembled in accordance with the method of and on the type of machine shown in our aforescribed copending application.

As stated, we have shown in the drawings three different species of toothed cam means in the

plug assembly to enlarge the enlargeable portions 42 of said blades as they enter the relatively restricted portion 43 of said slits 22 to positively cause the teeth 28 to become embedded in the slit end walls. In the embodiment of our invention shown in Figs. 4-9, we provide as this embodiment of cam means, a V-shaped or triangular longitudinal wedge portion 44 projecting upwardly from the inner end of each slit 22 and we provide at the inner end of each respective blade a 10 cooperating V-shaped longitudinal slot 46 of less width than said V-shaped wedge, whereby said wedges 44 may expand said slots 46 and hence legs 48 formed on the inner end of each blade to cause said toothed inner portions 30 of the 15 end walls of said blades to become embedded in the adjacent end wall portions 32 of said slits 22 as said blades are inserted within said slits 22 to cause said blades to be permanently retained within said slits. Figs. 4-7 show various steps in 20 the method of assembly of this embodiment, Fig. 4 showing the blade aligned with its respective slit, Fig. 5 showing the blade partially inserted within its respective slit with the inner ends of the legs 48 starting to contact the walls of the wedge 44, 25 Fig. 6 showing the wedge 44 starting to spread the legs 48 of the blade and Fig. 7 showing the legs 48 of the blade completely spread by the wedge 44 so that the teeth 28 thereof are positively embedded in the end walls of the slits. 30 Figs. 8 and 9 are side elevations respectively similar to Figs. 4 and 7, Fig. 9, however, showing each terminal 18 passing through its respective aperture 34, in this instance the upper end of the V-shaped slot 46 extending loosely through said 35 aperture as a space 50 is provided between the upper end of the wedge 44 and crotch of the V-shaped slot 46 without any clamping engagement at this point and having the end 36 thereof firmly clamped between the outer blade side wall 38 40 and adjacent slit side wall 40.

Figs. 10-15 illustrate the identical steps of assembly and the functioning of a different embodiment of our invention. In this instance, however, the cam wedge means instead of comprising the wedge 44 integrally projecting upwardly from the inner end of its respective slit 22, comprises the triangular shaped wedge 44' of greater width than the width of the V-shaped slot 46' having the upper end thereof integrally 50 frangibly attached to a leg 48 of said blade 20 by the frangible internal connection 52 joining an outer top edge of the wedge to the adjacent inner top edge of a blade leg 48 so that at all times the point of the wedge 44' lies in position 55 to project upwardly within the slot 42' on fracture of said frangible portion 52. On the further forcible insertion of said blade within its respective slit 22 from a position shown in Fig. 11 to the position shown in Fig. 12, the frangible portion 52 becomes broken so that the wedge 44' 60 may remain in the bottom of the slit 22 to function identically to the wedge 44 in the assembly of the blade within as described for the embodiment shown in Figs. 6 and 7, the functioning of 65 the other parts being similar to that described for the first embodiment.

Figs. 16-21 illustrate an embodiment having a third alternative species of cam means. In this embodiment the cam means is constructed as 70 follows: An enlarged aperture 34'' is provided at the inner end of a respective blade 20'' through which the outer end 36 of the terminal is adapted to extend. Said blade is also provided with a slit 54 extending from said enlarged aperture 75

34" to an outer end wall of the blade, said slit prior to insertion being of substantial depth. Upon the forcible insertion of such a constructed blade 20 within its slit 22, it is obvious that the 5 aperture 54 will be fast narrowed and the upper end of the blade portion 56 below said slit 54 will strike the blade portion 58 above said slit to cause the enlargable portion 42" of the blade around said aperture 34" to expand from the 10 position shown in Fig. 18 to the position shown in Fig. 19 to cause the teeth 28 on the inner end of said blade to become embedded in their respective inner portions 32 of the end walls of the slits, the end 36 of the terminal being 15 clamped between the outer side wall 38 of the blade and the adjacent outer slit wall 40 as in the other embodiments.

It is apparent therefore that we have provided novel types of connector blades and plugs and connector plug assemblies shown, which may be readily assembled by the mere positive insertion of the blades within their respective slits with the advantages explained above.

It is understood that our invention is not limited to the various embodiments shown and that various deviations may be made therefrom without departing from the spirit and scope of the appended claims.

What we claim is:

30 1. A connector plug assembly, comprising a one piece body member molded of rigid insulating material having a base having an inset central portion, a neck, a central aperture extending from said neck through said body to said inset base portion, spaced longitudinal slits extending inwardly from said base adjacent the outer ends of said inset portion and flat contact blade members initially of less width than the slits having the inner ends thereof contained within said 35 slits and substantially filling the upper portions thereof and having teeth on the inner portions of the end walls thereof embedded within the inner portions of the end walls of said slits, and apertures in the inner ends thereof, cam wedge 40 means in said plug assembly to cause said toothed inner portions of the end walls of said blades to become embedded in the adjacent end wall portions of said slits as said blades are inserted within said slits and be retained therein, and a 45 multi-terminal connector cord contained within the central aperture having each terminal wire thereof extending outwardly over said inset base portion through its respective blade aperture and the end thereof clamped between each outer 50 blade side wall and adjacent slit side wall.

55 2. A connector plug assembly, comprising a one piece body member having a base, a neck, a central aperture extending from said neck through said body, spaced longitudinal slits extending inwardly from said base connected to said central aperture, flat contact blade members initially of less width than the slits having the inner ends thereof contained within said slits and substantially filling the upper portions thereof 60 of and having teeth on the inner portions of the end walls thereof embedded within the inner portions of the end walls of said slits, and apertures in the inner ends thereof, cam wedge means in said plug assembly to cause said toothed inner portions of the end walls of said blades to become embedded in the adjacent end wall portions of said slits as said blades are inserted within said slits and be retained therein, and a multi-terminal connector cord contained within 65 the central aperture having each terminal wire

thereof extending outwardly through its respective blade aperture and the end thereof clamped between each outer blade side wall and adjacent slit side wall.

70 3. A connector plug assembly, comprising a one piece body member having a base, a neck, a central aperture extending from said neck through said body, spaced longitudinal slits extending inwardly from said base connected to said central aperture, a V-shaped longitudinal slot 75 wedge projecting upwardly from the inner end of each slit, flat contact blade members having the inner ends thereof contained within said slits and having teeth on the inner portions of the end walls thereof embedded within the inner 80 portions of the end walls of said slits, and each having a cooperating V-shaped longitudinal slot in the inner end thereof of less width than said V-shaped wedge whereby said wedges may expand said slots to cause said toothed inner portions of the end walls of said blades to become embedded in the adjacent wall portions of said slits as said blades are inserted within said slits and be retained therein, and a multi-terminal connector cord contained within the central aperture having each terminal wire thereof extending outwardly through the outer end of said V-shaped slot and the end thereof clamped between each outer blade side wall and adjacent slit side wall.

85 4. A connector plug assembly, comprising a one piece body member having a base, a neck, a central aperture extending from said neck through said body, spaced longitudinal slits extending inwardly from said base connected to said central aperture, each having a V-shaped longitudinal wedge projecting integrally upwardly from the inner wall of each slit, flat contact blade members having the inner ends thereof contained within said slits and having teeth on the inner portions of the end walls thereof embedded within the inner portions of the end walls of said slits, and each having a cooperating V-shaped longitudinal slot in the inner end thereof of less width than said V-shaped wedge 90 whereby said wedges may expand said slots to cause said toothed inner portions of the end walls of said blades to become embedded in the adjacent wall portions of said slits as said blades are inserted within said slits and be retained therein, and a multi-terminal connector cord contained within the central aperture having each terminal wire thereof extending outwardly through the outer end of said V-shaped slot and the end thereof clamped between each outer blade side wall and adjacent slit side wall.

95 5. A connector plug assembly, comprising a one piece body member having a base, a neck, a central aperture extending from said neck through said body, spaced longitudinal slits extending inwardly from said base connected to said central aperture, flat contact blade members having the inner ends thereof contained within said slits having teeth on the inner portions of the end walls thereof embedded within the inner portions of the end walls of said slits, each having a V-shaped longitudinal slot in the inner end thereof, and a triangular portion of greater width than said V-shaped slot 100 integrally frangibly attached to one end thereof and extending underneath said slot prior to forcible insertion of said blades within said slits broken on such insertion to provide V-shaped longitudinal wedge portions projecting upwardly

- from said slits to expand said V-shaped slots to cause said toothed inner portions of the end walls of said blades to become embedded in the adjacent wall portions of said slits as said blades
- 5 are inserted within said slits and be retained therein, and a multi-terminal connector cord contained within the central aperture having each terminal wire thereof extending outwardly through the outer end of said V-shaped slot
- 10 and the end thereof clamped between each outer blade side wall and adjacent slit side wall.
6. A connector plug assembly, comprising a one piece body member having a base, a neck, a central aperture extending from said neck through said body, spaced longitudinal slits extending inwardly from said base connected to said central aperture, flat contact blade members having the inner ends thereof contained within said slits having teeth on the inner portions of the end walls thereof embedded within
- 15
- 20

the inner portions of the end walls of said slits, each having prior to insertion an enlarged aperture in the inner end thereof and a slit extending from said aperture to an outer end wall whereby on forcible insertion of said blades 5 within said body slits the inner ends of said blades around said apertures may expand to cause said toothed inner portions of the end walls of said blades to become embedded in the adjacent wall portions of said slits as said 10 blades are inserted within said slits and be retained therein, and a multi-terminal connector cord contained within the central aperture having each terminal wire thereof extending outwardly through its respective blade aperture and 15 the end thereof clamped between each outer blade side wall and adjacent slit side wall.

CARL H. JUDISCH.
ARTHUR HOWARTH. 20
